UNITED STATES PATENT OFFICE.

VICENTE PINO, OF NEW YORK, N. Y.

CEILING AND WALL WASHING MACHINE.

Application filed March 10, 1927. Serial No. 174,304.

This invention relates to a new and useful device in the nature of a ceiling and wall cleaning and washing machine, particularly adapted for use to clean and wash 5 ceilings and walls of rooms.

The object of the invention is to provide a ceiling and wall cleaning and washing machine of novel construction and arrangement of parts, hereinafter more fully described, claimed, and illustrated in the accompanying drawings, in which:

Fig. 1 is a top plan view of my improved machine.

Fig. 2 is a front elevational view thereof.

Fig. 3 is a side elevational view thereof.

Fig. 4 is an enlarged transverse sectional view taken on the line 4—4 of Fig. 2.

Fig. 5 is a similar view to that shown in Fig. 3 of the other side of my improved 20 machine.

Fig. 6 is an enlarged vertical sectional view taken on the line 6—6 of Fig. 2.

Fig. 7 is a transverse enlarged sectional view taken on the line 7—7 of Fig. 6.

Fig. 8 is a similar sectional view taken on the line 8—8 of Fig. 2.

Fig. 9 is a fragmentary side elevational view, partly in section, of the extension member, as embodied in my improved 30 machine.

As here embodied my improved machine comprises a base 10, mounted on casters 11, so as to provide a portable machine which may be easily and readily rolled 35 about the floor of a room or the like. The upright members 12, are attached, at their lower extremities to the base 10, and extend upwardly therefrom vertically. The upright members 12 are provided with 40 grooved recesses adapted to slidably receive the extended elements 13 of the frame work 14. The tank 15, having a rounded or curved lower portion 16, and open at its upper extremity is mounted on the upper 45 portion of the frame work 14. The crank 17 is provided with a handle 18, and is attached to the shaft 19, rotatively mounted in the bracket 20, attached to the cross member 21, supported by the upright members 12. The 50 pinion 22 is attached to the shaft 19, and meshes with the gear rack 23, attached to the frame work 14. The above described construction being such as will permit the tank 15, to be raised or lowered, as may be desired, 55 by rotating or turning the crank 17.

The rods 24 and 25, are provided with

apertures, adapted to receive the brush members 26, extended therefrom, in opposite directions. The rods 24 and 25, are rotatively mounted in the ends of the tank 15. The 60 pinion 27 is attached to the rod 24, and meshes with the pinion 27' rotatively mounted on one end of the tank 15, the pinion 28' meshes with the pinion 27', and is similarly mounted on the tank 15, and 65 meshes with the pinion 28 attached to the shaft 25. The sprocket wheel 29, is attached to one extremity of the shaft 24. The sprocket chain 30 is extended over the sprocket wheel 29, and over the sprocket 70 wheel 32, attached to the armature shaft of the electric motor 33 of ordinary design and construction. The electric motor 33 is operatively connected to any convenient source of electric power, not shown in the 75 accompanying drawings. The above described construction being such as will permit the electric motor 33, to rotate the brush members 26. The crank 34, provided with a handle 35, may be removably attached to 80 the said armature shaft of the electric motor 33, as a means of manually rotating the brush members 26.

The tubular members 36 and 37, are attached to the curved lower portion 16 of the 85 tank, and are extended downwardly therefrom. The flexible tubular members 38 and 39 are attached to the lower extremities of the tubular members 36 and 37, respectively. The valve disc 40 is adapted to enclose or 90 cover the upper opening of the tubular member, and is attached to one extremity of the arm 41, preferably of spring steel, or the like, attached at its other extremity to the curved lower portion 16 of the tank 15, so as to normally hold the valve disc 40 in a closed position. The flexible member 42 is attached to the valve disc 40, and is extended over the side of the tank 15, and has attached at its free extremity, a ring member 43, or handle. 100 The tubular members 36 and 37, are provided with valves 44 and 45 respectively, adapted to close the said tubular members. The above described construction being such as will permit the amount of water, supplied 105 to the tank 15 through the tubular member 37 to be controlled or regulated by the disc member 40, and by the valve 45, and which will permit paint, tinting mixture, calcimine, or the like, placed in the tank 15, to be 110 retained therein, or drawn off therefrom, by the manipulation of the said valve 44. It

being understood that the flexible tubular member 39, may be connected to any convenient source of water supply, under pressure, and that a bucket, pail or the like, may be placed under the flexible tubular members to hold the said paint or water.

The electric motor 33 is mounted on the bracket 46, attached to the frame work 14. The shaft 47, is attached to the armature shaft of the electric motor 33, and is rotatively mounted on the frame work 14. The face cam 48, is attached to the extended extremity of the shaft 47, and is provided with a circumferential groove 49, helically cut or formed therein, as is common to face cams, of conventional design and construction. The roller 50, is adapted to engage in the circumferential groove 49 of the face cam 48, and is rotatively attached to the lever 51. The lever 51 is provided with an intermediate elongated aperture 52, adapted to engage the pin 53, attached to the frame work 14. The lever 51 is provided with extended elements 54 and 55 so as to form a forked portion adapted to engage the cylindrical member 56, attached to the shaft 57. The cylindrical member 56 is provided with gear teeth 58, meshing with similar gear teeth 59, formed or cut in the extended element 55 of the lever 51. The shaft 57 is rotatively mounted in the frame work 14, and is provided with an axial aperture, preferably of square cross section, adapted to removably receive the upper portion of the rod 60, which is provided with a lower extremity 61, adapted to engage in an aperture formed in the supporting member 62, attached to the above mentioned base 10. The rod 60 is provided with apertures adapted to receive the brush members 63, extended therefrom, in a downward position. The rod 60, is attached to the retaining member 64. The above described construction being such as will permit the electric motor 33 on the crank 34, to oscillate the brush members 63. The flexible tubular members 65 are attached to the lower rounded portion 16 of the tank 15, and to tubular members 66 and 67, attached to the reinforcing member 64, and are provided with a plurality of extended tubular members 68 and 69 respectively, positioned at an angle thereto. The above de-

scribed construction being such as will permit the water or paint in the tank 15, to be injected onto the brush members 63. It being understood that the above described construction is such as will permit of the operation of the brush members 63, when the tank 15, is in a lowered position, as clearly shown in Fig. 2.

As a means of permitting the brush members 63, to be operated when the tank 15, is in an upper or extended position, I have provided an extension member 70, provided with an axial aperture 71 adapted to engage in the extended element of the rod 60. The upper portion of the extension member 70 engages in the axial aperture formed in the shaft 57. The tubular member 67 is adapted to telescope into the tubular member 66, so as to permit the brush members 63 attached to the extension member 70, to be supplied with the said paint or water. The latter described construction being such as will permit the extension member 70 to be oscillated when the tank 15 is in an upper position.

It is obvious that I have provided an improved machine adapted to clean and wash ceilings and walls of rooms.

Having thus described my invention what I claim and desire to protect by Letters Patent of the United States is as follows:

In a ceiling and wall cleaning and washing machine of the class described, a tubular member and a second tubular member attached to the rounded lower portion of a tank and extended downwardly therefrom, a valve disc adapted to enclose the upper opening of the first mentioned tubular member, said valve disc attached to one extremity of an arm, said arm attached to the said lower rounded portion of the said tank, so as to normally hold the said valve disc in a closed position, a flexible member attached to the said valve disc, and extended over the side of the said tank, a ring member attached to the free extremity of the said flexible member, as a means of opening the said valve disc.

In testimony whereof I have affixed my signature.

VICENTE PINO.
